MACHINE FOR MANUFACTURING SHEET METAL SURFACING UNITS

Howard J. Little, Fort Thomas, Ky., assignor to
The Andrews Steel Company, a corporation of
Delaware

Application April 14, 1937, Serial No. 136,879

1 Claim. (Cl. 153—77)

This invention relates to the manufacture and fabrication of sheet metal material and particularly to the manufacture and fabrication of sheet metal strips which are used for surfacing units for walls, roofs, and the like, of buildings. Sheet metal is thin and flexible, and particularly so are sheet metal roofing and siding units which are of relatively large dimensions. To overcome this and give added rigidity and stiffness to the units, they are ordinarily corrugated with complementary elongated elevations and recesses alternately disposed across one dimension of the units. These units are laid with one side and end overlapping the corresponding opposite side and end of similarly constructed units. In surfacing coverings of this type, it is a problem, due to the forces of capillary attraction, to prevent water from creeping between the overlapping portions of the units beneath the surface covering. Furthermore, when sheet metal surfacing units are laid in overlapping relation, the overlapping margins are wavy and out of contact at various spaced intervals between places where nails are applied, thereby creating open spaces which give access to water. This is particularly true of the lower edge of the unit. Accordingly, it is the aim of the present invention to provide a machine for constructing said units.

The units are ordinarily provided with complementary elongated elevations and recesses alternately disposed across one dimension of the sheet, said corrugations being preferably continuous and uninterrupted. To interrupt the forces of capillary attraction in these conventional units, one marginal side edge may be advantageously formed with a beading that provides a recess on the underside and between the contacting surfaces of the overlapped sides of adjacent units. The beading is provided on that marginal side edge which is to overlap the opposite marginal side edge of a similarly constructed unit. A similar beading is provided on one marginal end transverse to the corrugations and near the edge to be in that portion of the end which overlies the opposite end of a similarly constructed unit. Thus in the surfacing layer composed of the overlapping units, the forces of capillary attraction will be interrupted throughout the overlapping portions, both longitudinally and transversely. The side and end of the unit which are provided with the beadings may be advantageously flexed below the underside of the unit so that when overlapped with the opposite side and end of similar units, the flexed side and end will be compressed to provide a con-

tinuous line contact when the units are nailed. This is particularly advantageous in respect to the beaded end of the unit.

For a better understanding of the invention, reference may be made to the accompanying drawings in which—

Fig. 1 is a perspective view of a sheet corrugating machine embodying the invention;

Fig. 1A is a detailed cross-sectional view taken on line 1a—1a of Fig. 2;

Fig. 2 is an end view of the rolls taken on line 2—2 of Fig. 1;

Fig. 3 is an enlarged detailed view of a section of one of the facing segments on the upper roll;

Fig. 4 is a top plan view of a surfacing unit formed on the machine;

Fig. 5 is a top plan view of similar surfacing unit formed on the machine;

Fig. 6 is a transverse cross-sectional view taken on line 6—6 of Fig. 4;

Fig. 7 is a transverse cross-sectional view taken on line 7—7 of Fig. 5;

Fig. 8 is a cross-sectional view taken on line 8—8 of Fig. 10;

Fig. 9 is a cross-sectional view taken on line 9—9 of Fig. 10;

Fig. 10 is a top plan view showing a section of a surfacing layer with the side edges of the units overlapped; and

Fig. 11 is a side view, partly in cross-section, of the flexed end and the opposite end of an undraped unit.

Referring specifically to the drawings in which like numerals have been used to designate like parts, a corrugating device comprising essentially a pair of corrugating rolls 1 and 2 are mounted in a pair of standards 3 supported on any suitable foundation 4. The lower roll 1 is preferably non-adjustable, whereas the other roll 2 is advantageously adjustably mounted in the standards, the adjustment being effected by bearing blocks 5 movable within recesses 6 in the standards in which the ends of the rolls are journaled. These blocks 5 may be conveniently manipulated by means of hand wheels 7 to position the roll 1 in relation to roll 2. Springs (not shown) are preferably interposed in the standards to impinge against the blocks 5 and normally hold the rolls slightly spaced apart. The corrugating rolls are driven by any suitable source of power typified herein by electric motor 8 which is connected to the rolls by any suitable gear mechanism housed within the casing 9. The driving mechanism is of conventional con-

struction and does not need to be described in detail.

The rolls are the same in general construction, each preferably having an hexagonal periphery to receive a facing that may either be integral or conveniently divided into any number of separate segments. The segments on one roll are provided with the female dies and those on the other are provided with the male dies for forming the beadings, these and the corrugations being adapted to cooperate or intermesh as the rolls are rotated, with the sheets to be corrugated fed therebetween. Roll 1 is provided with any number of facing segments 10, each having a flat under side face 11 shaped to conform to a face portion on the periphery of the roll 11a, and an outer face provided with recesses 12 and elevations 13 alternately disposed. These are contoured to impart to the corrugated sheet 14 recesses 15 and elevations 16 which are semi-cylindrical and of equal or unequal radii. One (or more) of the segments is also provided on one of the marginal elevations with a raised portion 17 disposed along the length of the elevation. This may be formed integral with the facing segment or separately attached thereto as by a bar inserted within a groove substantially as shown in connection with the hereinafter described male die forming the circumferential beading. The segments 18 provided on the other roll 1 are of the same general construction as the segments 10 on the upper roll, the only difference being that instead of the raised portion 17 a recess 19 is provided and positioned to receive the raised portion 17 on the upper roll in order to form the side marginal beading 20 in the surfacing unit. It, too, may be formed in the facing segment or by a grooved bar inserted within a recess in the segment and attached thereto. The width of two segment's facing surface as shown corresponds to the width of a standard size sheet which is to be corrugated. The rolls, however, may be larger or smaller to accommodate more or less than six facing segments, but six facing segments are the preferred number to be employed. These may be of a width corresponding to that of one or more standard sheets. As shown, they are disposed to corrugate three sheets upon one revolution of the rolls. In other words the faces of two segments are equal to the width of one standard sheet. The widths of the segments may be such as to corrugate one or two sheets upon each revolution of the rolls.

One or both ends of the facing segments 10 are each provided with a transverse projection 21 disposed to cooperate with corresponding recesses 22 formed on segments 16. The projections 21 and recesses 22 do not extend entirely across the width of the segments but extend from the end of the longitudinally disposed projection and the recess to a distance slightly short of the width of the segments, thereby forming a transverse beading 23 terminating slightly short of the side edge opposite to that which is provided with the marginal side beading 20. This leaves the overlapped edge 24 free of any raised portion which might tend to separate the overlapped beaded side edge. The transverse beading will terminate in the recess 15 which is to receive the beaded marginal side. The side edge with the beading 20 terminates with the wall of the marginal corrugation extending downward. The opposite side edge may terminate with the side

wall of the corrugation extending downward (Figs. 4 and 6) or upward (Figs. 5 and 7).

To form a flexed end 25 on the bottom end of the sheet, the left hand end of the upper roll, or rather the segments mounted thereon, may be slightly tapered upward and increased gradually in diameter toward the end whereas the corresponding end of the lower roll or the segments thereon may be tapered downward and decreased gradually in diameter toward the end corresponding to upward inclination of the upper roll. Or to avoid any special construction in the contour of the rolls or segments, the male and female dies for forming the transverse beading may be mounted on respective insert 26 and 27 within an annular groove formed in the segments and fastened thereto. One portion of the male die carrying insert will be provided with a downwardly inclined face 28 and the corresponding portion of the female die will be upwardly inclined at 29. The sheet to be corrugated will be fed into the machine with the side edge in alignment with the outer edges of the inserts. If it should be desired to downwardly flex the opposite end of the sheet, a similar construction may be provided on the right hand ends of the rolls.

The blank metal sheets from which the surfacing units are to be corrugated, are cut into desired sizes and then fed between the corrugating rolls. In order to facilitate feeding the blanks 30 to the corrugating machine, a feed table 30 may be positioned adjacent the rolls, and at spaced intervals the table is cut away at 31 to provide for any number of endless feed chains 32 to move and automatically feed the sheets to the embossing rolls. Each of the endless chains is provided with arms 33 arranged in parallelism so that when rotating they engage the edge of the sheets and feed them to the corrugating rolls. The length of the sheets vary, some being short and some being longer, thus it is preferable to provide several feeding devices, for by having several of them, sheets of varying lengths can be readily handled without making any adjustment. A guide rail device 34 or other suitable end guide may be positioned loosely on the table against which one end of the sheets is contacted to align them as they are being fed through the corrugating rolls.

The endless feed chains 32 are fitted over sprockets 35 mounted on idle shaft 36 and similar sprocket (not shown) mounted on a driven shaft (not shown) running parallel to shaft 36 and adjacent the lower roll 1. One end of the driven shaft is journaled in bearing 37 in the standard. The table may be adjusted in position adjacent the corrugating rolls by means of hand wheels 38.

In the embodiment of the machine herein illustrated the circumferentially disposed projections and recesses for forming the transverse beading are formed on the left hand ends of the corrugating rolls but it will be understood that they could, if so desired, be provided on the right hand end of the roll in a similar construction.

The corrugated sheets are preferably corrugated with the side edge and end edge beading downwardly pressed or in other words, the corrugated sheet is discharge from between the rolls with the weather exposed face down. The non-weather face is that provided with the side and end beading recesses.

These sheets are laid as shown in Fig. 10 with the beaded side edge overlapping the opposite non-beaded side edge of a similarly constructed unit, thereby providing a space (Fig. 8) length-

wise between the contacting surfaces of the overlapping sheets. And the bottom beaded end overlaps the opposite upper non-beaded end of a similarly constructed sheet, thereby forming also a space (Fig. 9) crosswise between the contacting surfaces of the overlapping sheets. The edge of the flexed end 25 rests upon the face surface of the undersheet (Fig. 11) and is pressed down to bring the underface in line contact (Fig. 9) with the under sheet when the nail 38 is driven home.

In the apparatus illustrated, the sheet is corrugated, beaded, and flexed in a single operation. Although this is a preferred expedient of manufacture as the machine is consolidated into a single unit and all steps of manufacture are effected in a single operation, it will, of course, be understood that the invention may be practiced by dividing the machine into separate units for performing the individual operations. Rolls have also been illustrated as the preferred means for carrying out the various steps of the process, but other means are also suitable.

While I have described one preferred embodiment of the machine and one preferred embodiment of corrugated roofing unit for the purpose of illustrating the invention, it will be understood that various changes in details of construction may be made without departing from the spirit of the invention.

I claim:

A machine for corrugating sheet metal surfacing units comprising rolls provided with co-operating male and female dies for forming corrugations across one dimension of the sheet, means disposed longitudinally of the rolls and at spaced intervals on the periphery of the rolls for forming a marginal beading along one of the corrugations, and bead forming means on one end of the rolls extending circumferentially from the end of the longitudinally disposed beading means to a point terminated short of the next adjacent longitudinally disposed beading means.

HOWARD J. LITTLE.
